Application March 1, 1934, Serial No. 713,547

13 Claims. (Cl. 290—38)

This invention relates to engine starting mechanism of the type in which the cranking connection is automatically established by energization of the starting motor and is interrupted when the engine starts, and more particularly to a device for electrically controlling the cranking connection.

It is an object of the present invention to provide a starting mechanism of the above type which is efficient and reliable in operation and simple and economical in construction.

It is another object to provide such a device in which the cranking connection is in the form of gears arranged to mesh and demesh by bodily movement transverse to their axes of rotation.

It is a further object to provide such a device in which the cranking connection is positively maintained or locked until the engine starts.

It is another object to provide such a device in which the lock is rendered effective magnetically by the initial heavy flow of cranking current and in which the reduction of current when the engine starts is used to break the cranking connection.

Further objects and advantages will be apparent from the following description taken in connection with the accompanying drawing in which:

Fig. 1 is an end view of a preferred embodiment of the device partly in section and partly diagrammatic showing the parts in normal or idle position.

Fig. 2 is a similar view showing the parts in cranking position; and

Fig. 3 is a side elevation partly in section showing the parts in idle position.

Referring first to Fig. 3 of the drawing, there is illustrated a starting motor 1 having an extended armature shaft 2 on which is freely journaled a driving member in the form of a pinion 3. The pinion 3 is connected to rotate with the armature shaft 2 by means of a suitable yielding connection illustrated in the form of a coil spring 4 anchored at 5 to a driving head 6 fixed on the armature shaft and anchored at 7 to a driven head 8. The driven head 8 is connected through an overrunning clutch 9 to an extension 11 of the pinion 3 whereby the pinion is permitted to overrun the armature shaft but is yieldably driven therefrom.

A transmission member in the form of an intermediate pinion 12 is mounted to mesh with the driving pinion 3 being free to planetate around the axis of the armature shaft. As here shown this is arranged by mounting the intermediate

pinion 12 on a bearing member 13 which is suitably fixed in a bracket formed by plates 14 and 15 journaled on smooth extensions of the driven head 8 and pinion 3 respectively, whereby the intermediate pinion 12 can swing into and out of mesh with a member such as a flywheel gear 16 of the engine to be started.

According to the present invention means are provided for locking the intermediate pinion 12 in driving engagement with the engine member 16 during the cranking operation in order to prevent disengagement thereof when the engine passes over its compression points or as a result of a false start of the engine. As here shown this locking means is in the form of a toggle device 15 comprising an arm 17 pivoted at 18 to any suitable fixed support and pivoted at 19 to a second toggle arm 21 which in turn is pivoted to an extension 22 (Fig. 3) of the bearing member 13 on the swinging bracket 14, 15. The dimensions of the toggle arms 17 and 21 are such that when the arms are straightened out in locking position as illustrated in Fig. 2, the intermediate pinion 12 is in full mesh with the engine gear 16. The locking position of the toggle arms is preferably defined by suitable means such as shoulders 22 and 23 on the toggle arms 17 and 21 respectively which are arranged to engage when the toggle is in locking position.

Means are provided for bringing the toggle 30 device into full locked position in response to the initial heavy current flow when cranking starts, and for breaking the toggle in response to the reduction in current flow when the cranking load is relieved as the engine becomes self-operative. As here shown this means comprises an electromagnet 24 having a few turns of heavy wire placed in series in the starting circuit which comprises the battery 25, the starting switch 26 and the starting motor 1. Electromagnet 24 is 40 preferably of the so-called iron-clad type comprising a central pole piece 27 and an outer shell 28 of magnetic material mounted on a suitable fixed pivot as indicated at 30.

A magnetic plunger 29 is arranged to slide in 45 a suitable non-magnetic guide member in the form of a tube 31, and is arranged to be attracted by the pole piece 27 when it is brought into proximity to the electromagnet 24. Plunger 29 is adjustably mounted on a rod 32 the lower 50 end of which is provided with a cross head having a slot 33 adapted to receive an extended portion 34 (Fig. 3) of the toggle pivot 19. The dimensions of the rod 32 and slot 33 are such that when the toggle is placed under tension by the 55

swinging of the bracket 14, 15 by the action of the starting motor 1, the plunger 29 will be brought into proximity to the electromagnet 24; and when the plunger 29 is thereupon attracted by the pole piece 27 the lower end of the slot 33 will engage the pivot 19 and move the toggle into fully locked position as illustrated in Fig. 2. Yielding means in the form of a spring 40 is provided for causing the upper end of the slot 33 to strike the toggle pivot 19 and break the toggle when the plunger 29 is released by the weakening of the electromagnet 24 when the engine starts.

In order to assist in differentiating between a false start and a true start of the engine, a time delay is preferably provided for preventing the immediate breaking of the toggle in response to a momentary weakening of the electromagnet 24 which might be caused by a false start of the engine. As here shown, this time delay is in the form of a dash pot provided by the plunger 29 in the tube 31. For this purpose the pole piece 27 is arranged to close the free end of the tube 31, and an opening 35 is provided in the tube 31 at a suitable distance below the pole piece in order to permit free movement of the plunger 29 below said opening. An adjustable bleeder in the form of a channel 36 having a restricted passage regulated by the needle valve 37 is provided for regulating the time delay, and a larger opening 38 controlled by a check valve 39 is preferably provided in order to permit rapid upward movement of the toggle and rod 32 into locking position.

Suitable means such as indicated generally at 41 are provided for adjusting the tension of the releasing spring 40, and the adjustable connection indicated at 42 between the plunger 29 and rod 32 permits the regulation of the air gap 43 between the plunger 29 and the pole piece 27. The device may thus be adjusted to release at any desired strength of flux through the electromagnet such as that corresponding to the free spinning condition of the starting motor when the engine starts.

In the operation of this device, starting with the parts in the positions illustrated in Fig. 1, closure of the starting switch 26 causes energization of the starting motor 1 whereby the driving pinion 3 is rapidly accelerated. The intermediate pinion 12, due to its rotational inertia is moved by the torque of the driving pinion 3 into engagement with the engine gear 16, whereupon the pinion 12 is moved into full mesh with the engine gear by virtue of the driving reaction of the gearing. During this time the toggle 17, 21 is placed under tension whereby the rod 32 is raised until the plunger 29 comes within the zone of influence of electromagnet 24 which is at this time strongly energized by the initial heavy flow of cranking current as the starting motor initiates the cranking operation. The plunger 29 is thereby caused to draw the toggle 17, 21 into its locking position as illustrated in Fig. 2 where it is maintained during the cranking operation irrespective of any tendency which the engine gear 16 might have to overrun as the engine passes over its compression points or because of weak explosions of the engine.

When the engine starts, the relief of the cranking load on the starting motor causes the electromagnet 24 to be weakened sufficiently to release the plunger 29 which moves slowly downward under the action of the spring 40 as retarded by the dash pot time delay. As soon as the plunger 29 reaches the opening 35 in the tube 31 it is permitted to move freely, and the upper end

of the slot 33 strikes the toggle pivot 19 breaking the toggle and permitting the bracket 14, 15 to swing back to idle position.

During the period of the time delay, the intermediate pinion 12 is driven by the engine gear 16, the overrunning clutch 9 permits the driving pinion 3 to overrun the armature shaft 2 whereby the starting motor 1 is not driven by the engine and is therefore not accelerated above its free-running speed. 10

In some installations it may be preferred to omit the overrunning clutch 9 and connect the driving pinion 3 directly to the driven head 8. With this arrangement, when the engine starts the motor is driven from the engine until the gearing is disconnected. If the disconnection does not take place until the motor has been accelerated above its free-spinning speed, the current flow through the motor will be reduced to a value less than the free-spinning current of the motor. The electromagnetic device may therefore be so adjusted as to release only at a lower current value than the free-spinning current. Obviously this maintains the gearing connection locked until the engine has become self-operative and accelerated considerably above cranking speed, which assures the continuity of the cranking operation until a true start has been secured.

When the electromagnetic device is adjusted to release only at amperages below free-spinning values, the dash pot time delay becomes unnecessary and may be omitted.

Although but one embodiment of this invention has been shown and described in detail, it will be understood that other embodiments are possible and various changes may be made in the details and arrangements of the parts without departing from the spirit of the invention as defined in the claims appended hereto. 40

What is claimed is:

1. Engine starting mechanism including a motor, a driving member connected thereto, a transmission member movable thereby into driving engagement with a member of an engine to be started, means for positively locking the transmission member in driving position and means responsive to the reduction in current caused by the acceleration of the starting motor when the engine starts for releasing said locking means. 45

2. Engine starting mechanism including a motor, a driving member connected thereto, a transmission member movable thereby into driving engagement with a member of an engine to be started, means for positively locking the transmission member in driving position, means responsive to the heavy cranking current of the motor for rendering said locking means effective and means responsive to the reduction in current caused by the acceleration of the starting motor when the engine starts for releasing said locking 60 means.

3. Engine starting mechanism including a motor, a driving member connected thereto, a transmission member movable thereby into driving engagement with a member of an engine to be started, means for holding the transmission member in driving position, means responsive to the heavy cranking current of the motor for rendering said holding means effective, means responsive to the reduction in current when the engine starts for releasing said holding mechanism and means for delaying such release for a predetermined time after such reduction in current takes place. 65

4. Engine starting mechanism including a 70

motor, a driving member connected thereto, a transmission member movable thereby into driving engagement with a member of an engine to be started, means including a toggle device for holding the transmission member in driving position, means responsive to the heavy cranking current of the motor for straightening said toggle for rendering said holding means effective, and means responsive to the reduction in current when the engine starts for breaking said toggle to release the holding means.

5. Engine starting mechanism including a motor, a driving member connected thereto, a transmission member driven from said driving member and bodily movable transverse to its axis into and out of engagement with a member of an engine to be started, means including magnetic means responsive to the cranking current through said motor for locking the transmission member in engagement with the engine member and means responsive to the relief of the cranking load when the engine starts for releasing said locking means and returning the transmission member to idle position, said locking and releasing means including adjustable means whereby the releasing means may be arranged to function at a predetermined value of the cranking current.

6. Engine starting mechanism including a motor, a driving member connected thereto, a transmission member bodily movable transverse to its axis into and out of engagement with a member of an engine to be started, means including magnetic means responsive to the cranking current through said motor for locking the transmission member in engagement with the engine member, means responsive to release of the cranking load when the engine starts for releasing said locking means, means for delaying the release of the locking means for a predetermined time after the engine starts, and an overrunning driving connection between the driving member and the transmission member.

7. Engine starting mechanism including a motor, a driving member connected thereto, a transmission member driven from said driving member and bodily movable transverse to its axis into and out of engagement with a member of an engine to be started, means including a toggle device and magnetic means responsive to the cranking current through said motor for straightening said toggle and thus locking the transmission member in operative engagement with the engine member and means responsive to relief of the cranking load when the engine starts for breaking said toggle and returning the transmission member to idle position.

8. An electrical starting system for internal combustion engines including a motor, a driving pinion rotated thereby, an intermediate pinion driven from the driving pinion and mounted for bodily movement transverse to its axis into driving engagement with a gear on the engine to be started, yielding means biasing the intermediate pinion toward idle position, means for locking the intermediate pinion in driving position, means for tripping said locking means, magnetic means responsive to cranking current for holding the tripping means during the cranking operation

and means for adjusting the effectiveness of said magnetic holding means whereby the reduction in current when the engine starts permits the tripping means to release the locking means for the intermediate pinion.

9. An electrical starting system for internal combustion engines including a motor, a driving pinion rotated thereby, an intermediate pinion driven from the driving pinion and mounted for bodily movement transverse to its axis into driving engagement with a gear on the engine to be started, yielding means biasing the intermediate pinion toward idle position, means for locking the intermediate pinion in driving position, means for tripping said locking means, magnetic means responsive to cranking current for holding the tripping means during the cranking operation and means for delaying the action of the tripping means for a predetermined time after the engine starts, said means being arranged so as not to interfere with the locking action of the locking means.

10. Engine starting mechanism including a motor, a driving member constantly connected for rotation therewith, a transmission member movable thereby into driving engagement with a member of an engine to be started, and means including electromagnetic means responsive to current traversing the starting motor for positively locking the transmission member in driving position until said cranking current is reduced to a value less than the free-spinning current of the motor.

11. Engine starting mechanism including a motor, a driving member constantly connected for rotation therewith, a transmission member movable thereby into driving engagement with a member of the engine to be started, means including electromagnetic means energized by current traversing the starting motor for positively locking the transmission member in operative engagement with the engine member, said locking means including elements adjustable to release the transmission member in response to a reduction of current flow through said motor to a predetermined value below the value of the free-spinning current thereof.

12. Engine starting mechanism including a motor, a driving member constantly connected for rotation thereby, a transmission member movable thereby into driving engagement with a member of the engine to be started, means for positively locking said transmission member in operative position, and means responsive to a predetermined acceleration of the starting motor for releasing said locking means.

13. Engine starting mechanism including a motor, a driving member constantly connected for rotation thereby, a transmission member movable thereby into driving engagement with a member of the engine to be started, means for positively locking said transmission member in operative position irrespective of the driving reaction between the parts, and means responsive to a predetermined acceleration of the starting motor by the engine member when the engine starts for releasing said locking means.
